UNITED STATES PATENT OFFICE.

WILLIE A. SHIELDS, OF BIRMINGHAM, ALABAMA.

APPLIANCE FOR APPLYING AND REMOVING GARMENT-BAGS.

1,304,913.

Specification of Letters Patent. Patented May 27, 1919.

Application filed February 18, 1919. Serial No. 277,898.

To all whom it may concern:

Be it known that I, WILLIE A. SHIELDS, a citizen of the United States of America, residing at Birmingham, in the county of Jefferson and State of Alabama, have invented 5 certain new and useful Improvements in Appliances for Applying and Removing Garment-Bags, of which the following is a specification.

10 My invention relates to an apparatus for applying and removing the bags used to protect laundried or dry cleaned garments.

The object of my invention is to facilitate 15 the handling of garment protecting paper bags such as are commonly used in laundries and dry cleaning establishments so that they can be readily applied to the garment or removed from the garment when it is necessary to inspect the latter. The garment to 20 be inclosed within the paper bags are of widely varying lengths and bags of corresponding lengths are used. With this in view my invention is especially adapted to handle with equal facility the various 25 lengths of bags and comprises essentially a hanger rod from which the garment by means of its hanger is suspended and which forms a guide for a bag carrying slide. These bags have a top opening through 30 which the hanger rod passes, thus enabling the bag to be grasped by a clip on the slide, and slipped with it up or down on the rod until the bag's bottom end stands slightly above the garment hanger.

35 It is a further object of my invention to adapt the bag carrying slide to frictionally engage the rod so that it will stand at any height to which it may be adjusted so as to support the bag in the most convenient position.

40 A further object is to provide the rod with a stop which will arrest the bag carrying slide at the limit of its downward movement, so that a continued pull on the bag will serve 45 to disengage it from the slide clip and permit it to be drawn down into position over the garment with the garment hanger hook projecting through its top opening.

50 My invention also comprises the novel de- tails of construction and arrangements of parts, which in their preferred embodiments

only are illustrated in the accompanying drawings which form a part of this specification, and in which:

Figure 1 is a front elevation of my appliance showing the bag in full lines in elevated position and in dotted lines covering a garment. 55

Fig. 2 is a side view of Fig. 1.

Fig. 3 is an enlarged side elevation of the bag carrying slide. 60

Fig. 4 is a sectional view through the bag carrying slide taken on the line 4-4 of Fig. 3, and showing it in engagement with its arresting stop near the base of the hanger rod. 65

Similar reference numerals refer to similar parts throughout the drawings.

As illustrated, my invention comprises a hanger rod 1, preferably formed of a rectangular bar having at its lower end a hook 2 and adjacent to the hook a stop notch 3. This rod at its upper end is reduced and threaded so as to be screwed into a ceiling plate 4 attached by screws or in any other suitable manner to the ceiling or any suitable 70 overhead support. Mounted to slide on the rod is a slide 6 having a rectangular opening extending vertically therethrough which fits three sides of the square hanger rod snugly but is spaced from the fourth side 80 which has the notch 3 so as to leave a spring housing 7 therein in which is mounted a flat spring 8 having its ends bent toward and frictionally engaging the rod. This spring has fast thereto a pin 9 which passes outwardly through an opening 10 in the slide casing and has its outer end engaged and pressed inwardly by the free end of a flat spring 11 which is made fast at one end by a screw 12 to a boss 13 on the slide and which 90 is intermediately perforated for the passage of a screw 14 which is screwed into the slide and which has threaded thereon a wing nut 15 which by engaging the spring 11 nearest its center will control the pressure exerted 95 thereby through the pin 9 onto the friction spring 8. The slide at one side is provided with a pair of perforated ears 16 between which is pivotally mounted a bag clip 17 having its bag engaging surface 18 serrated 100 or roughened and pressed against the slide by the action of a coil spring 19 working be-

tween the slide and the other end of the clip. On the side of the slide opposite the clip I provide a lug 20 to which a cord 21 is secured, this cord being passed upwardly about a pulley 22 rotatably mounted in a pulley housing 23 suitably connected on or near the top of the rod. The cord thence passes about a second pulley 24 made fast to the ceiling or overhead support and has a handle 25 at its free end which hangs sufficiently spaced from the rod to clear the widest bag.

In operation, the wing nut 15 is adjusted to cause the spring 8 to frictionally grip the rod and hold the slide thereon in any position to which it may be set while supporting the heaviest type of paper bag 26. This bag, which is typical of any bag generally used in the laundry and dry cleaning business, is provided with a top opening through which the hook end 2 of the rod 1 is passed and the bag is slipped up over the rounded bottom end 27 of the slide and is caught at one side under the clip 17, thereupon the handle 25 is grasped and the bag carrying slide drawn up until the bottom end of the bag will clear the hook 2. Thereupon the garment 28 to be placed in the bag is mounted on any suitable type of hanger 29 and the hook 30 of the latter is hung on the hook 2 of the rod. The operator then grasps the open bottom end of the bag and pulls it down over the garment, the bag carrying slide being drawn downwardly therewith along the rod until the lower end of the spring 8 snaps into the notch 3 which arrests the slide, whereupon a continued pull on the bag will disengage it from the clip 17 and enable it to be drawn down over the garment hanger exposing the hook 30 of the latter and completing the bagging operation. To remove the bag from a garment for inspection or for any other reason, the garment with the bag thereon is hung from the hook 2, the bag is raised and caused to engage under the clip 17 and then the handle 25 is grasped and the slide raised until the garment is exposed. The rod is made long enough to accommodate the longest type of bag but it is equally available for the short bags as the operator merely draws up the bag carrying slide far enough to expose the garment or the hook 2.

The type of slide which I have shown is that which I consider preferable, but its construction may be varied without departing from the spirit of my invention. In like manner other types of hanger rods may be substituted for the preferred form illustrated.

This invention is not intended to be restricted in scope to the specific embodiments shown, but comprises such modifications as

come within the spirit and scope of the claims.

Having thus described my invention, what I claim as new and desire to secure by Letters Patent, is:—

1. In an apparatus of the character described, an elongated hanger rod having means at one end to attach it to an overhead support and having means at the other end for the suspension of a garment hanger, a slide vertically adjustable on the hanger rod and having means to frictionally engage the rod and hold the slide thereon in any desired position, bag engaging means carried by said slide, and means to move the slide on the rod.

2. In an apparatus of the character described, an elongated hanger rod having means at one end to attach it to an overhead support and having means at the other end for the suspension of a garment hanger, a slide vertically adjustable on the hanger rod and having means to frictionally engage the rod and hold the slide thereon in any desired position, a friction grip bag engaging means carried by said slide and adapted to draw the slide down when the bag is pulled down, and a stop to limit the downward movement of the slide on said rod and cause the automatic release of the bag from the friction grip.

3. In an apparatus of the character described, an elongated hanger rod having at one end means to attach it to an overhead support and at the other end means to support a garment hanger, said rod having a flattened vertical face, a slide adapted to slip up and down on the rod and comprising an element which frictionally engages said flattened face of the rod, spring means to control the frictional engagement of said element with the rod, a spring bag holding clip on said slide, a stop to limit the downward travel of the slide, an overhead pulley, and a pull cord passed over said pulley and made fast at one end to said slide to vertically adjust the latter, substantially as described.

4. In an apparatus of the character described, an elongated square hanger bar having at its upper end means to attach it to an overhead support and having at its other end a hook for supporting a garment hanger, there being a notch near the bottom of one flat face of said bar, a slide vertically adjustable on the bar and having a recess therein opposite the notched face of the bar, a spring member engaged in said recess and adapted at its ends to press against said notched face of the bar, said spring member having a stud projecting outwardly through the slide, a spring mounted on the outside of the slide and engaging said stud,

means to regulate the pressure of the spring on said stud, a spring-pressed bag engaging clip on said slide, a pulley mounted near the top of said bar, a second pulley spaced 5 from the bar and mounted on an overhead support, and a flexible connection made fast at one end to the slide and passing over said

pulleys and having a handle at its other end, substantially as described.

In testimony whereof I affix my signature. 10

WILLIE A. SHIELDS.
